SKI CREEPER

Benjamin Held, Brooklyn, and Aryan Shayne,
New York, N. Y.

Application August 31, 1938, Serial No. 227,732

5 Claims. (Cl. 280—11.13)

Our invention relates to so-called creepers which are used in connection with skis, primarily to permit the user thereof to go up a grade without slipping backward; as is well known, the use of 5 creepers is also advantageous in coasting and other kinds of travel, the creepers having the effect of slowing up the coasting speed and of giving to the user greater control over his actions.

The principal object of our invention is to provide a creeper which is effective and light in weight, and which also may be quickly and easily attached to or removed from the ski. Another object of our invention is to provide convenient means for attaching the creeper to the rear end 10 of the ski which means will effectively hold the creeper on the ski under suitable tension, but which, nevertheless, will permit quick removal of the creeper. Other objects and advantages of our invention will appear to those skilled in the art from the following specification, taken in connection with the drawing, in which—

Figure 1 shows the forward or toe end of our creeper, viewed from the bottom;

Fig. 2 shows the rear end thereof, viewed from the top;

Fig. 3 is a cross section on the line 3—3 of Fig. 1;

Fig. 4 is a cross section on the line 4—4 of Fig. 1;

Fig. 5 is a cross section on the line 5—5 of Fig. 2;

Fig. 6 shows the form of a stamping which is used as a clamp as will be hereinafter described;

Fig. 7 is a bottom view of the toe of the ski 35 with our creeper affixed thereto;

Fig. 8 is a side view of the rear end of the ski with our creeper affixed thereto;

Fig. 9 is a vertical longitudinal section of the rear end of the ski with our creeper affixed thereon; and

Fig. 10 is a detail view of our buckle in process of being separated.

Referring to the drawing, the creeper proper is shown at 1. As is understood in the art, it is preferable to make the creeper out of a strip of the skin of a fur-bearing animal; seal-skin is entirely suitable for this purpose. As is also understood, the creeper is so cut from the hide that the hair normally lies flat thereon and extends parallel to the length of the creeper, so that the creeper will slide smoothly over the snow when the ski is running in a forward direction but will create resistance to backward travel of the ski. We 55 prefer to use, as the creeper proper, a strip of

seal-skin, with the hair remaining thereon and without reenforcement of any kind.

The forward or toe end of our creeper comprises a loop 2 of heavy cord, the free ends of which are positively held together by a metal clamp 6. This clamp is stamped out of suitable metal, such as brass,—the form of the stamping being shown in Fig. 6. The stamping comprises a central body portion 7 with a plurality of prongs 8, 8' on each side thereof, the prongs on one side being staggered with respect to those on the opposite side. In the body 7 of the stamping, U-shaped cuts are made so that portions 9 of the material of the stamping can be bent out of the plane thereof to grip the cord. Similarly, notches are cut in the ends of the stamping so that additional portions, 10, thereof can also be bent inwardly to grip the cord. The two ends of the cord are placed adjacent the stamping and the latter is then bent over the ends of the cord in order positively to grip it, as shown in Fig. 3. A piece of tape 11, made out of suitable material, such as heavy canvas, is then folded over the clamp 6 and sewed, as indicated at 12, so as tightly to hold the clamp and the ends of the cord within the fold of the tape.

The other end of the tape 11 and the tapered end 13 of the creeper are placed between pieces of leather or other suitable material 14, which are generally in the form of a trapezoid, and the tape, the end of the creeper, and the two pieces 30 14 are then firmly sewed together.

Affixed to the upper or skin side of the creeper and extending throughout the greater part of its length and also having a free end extending beyond the rear end of the creeper, is another strip 35 15 of tape, made of heavy canvas or other suitable material. The strip of tape is affixed to the fur strip by stitching 15', or in any other suitable way. This strip of tape has two functions, namely, to cooperate with the ski to prevent lateral displacement of the creeper (as will be more fully explained hereinafter) and to enable the creeper to be attached to the rear end of the 40 45 ski.

To accomplish the latter function we employ a novel form of buckle. This comprises a plate 16 permanently fastened to the upper side of the ski not far from its rear end, the screws 17 or other suitable means being used to fasten the plate to the ski. The rearward end of the plate 16 is bent upward and back on itself, as indicated at 18, thus forming a channel in which one leg of the partially closed U-shaped rod 19 may 50 55

be inserted. The channel is so proportioned with respect to the form of one end of the rod 19 that the latter may be removed from the channel laterally by slightly turning the rod with respect to the plate 16. In Fig. 10, the rod is shown in the process of being removed from the channel. The end 20 of the rod 19 is bent so as to form a small hook-like member which, when the buckle is under tension, prevents removal 10 of the rod from the channel by lateral or other motion. The other member of the buckle comprises a plate 21 which, like the plate 16, has one end, 22, thereof bent upwardly and back upon itself to form another channel which holds the 15 other leg of the rod 19. In this case, however, the channel is so proportioned with respect to the rod and the hook-line portion 23 thereof that the rod may not be removed from the channel formed by the member 22, although the rod 20 is free to turn within the channel.

The plate 21 bears upstanding flanges 24 along the sides thereof, the two flanges, together with the plate 21, forming a groove in which the free end of the strip 15 may be inserted. To grip the strip tightly in the groove formed by the flanges 24 we provide a pressure member 25 which is pivoted on a shaft 26 carried by the two flanges 24. The member 25 is composed of a flat portion extending on one side of the shaft 26 and a shorter portion which may be curved, also extending from the shaft 26, preferably at an acute angle with respect to the flat portion. As will readily be understood, the strip 15 is clamped in the groove between the flanges 24 by inserting it therein beneath the pressure member 25, the latter then being turned in clockwise direction so that the shorter portion thereof tightly grips the tape between it and the plate 21.

In use, our ski creeper is affixed to the ski 40 27 by slipping the loop 2 over the toe 28 of the ski, as shown in Fig. 7, which is a view taken from underneath the ski with the toe-end of the creeper affixed thereto. The strip 15, which extends beyond the rearward end of the creeper, 45 is then bent around the rear end of the ski, placed in the groove between the flanges 24 of the buckle and under the member 25, which, at that time, is not clamped down on the strip. The U-shaped rod 19, permanently affixed as above described to plate 21, is thereupon inserted in 50 the channel formed by the bent back portion 18 of the plate 16. The strip 15 is then pulled tight and the pressure member 25 clamped down thereon. The ski, with the creeper attached, is then ready for use.

Normally, a ski is provided, on the lower surface thereof, with a longitudinal groove 29. In placing our creeper on a ski, the strip of tape 15 is made to engage the groove 29, thereby holding the creeper against lateral motion. The use of the strip 15 for this purpose makes it unnecessary to utilize straps which extend from the creeper over the sides of the ski, and which are sometimes used to prevent lateral motion of the creeper. Thus the strip 15, in cooperation 65 with the groove 29 in the ski, provides not only a simpler but a more effective means for preventing lateral motion of the creeper.

To remove the creeper, it is only necessary 70 to detach the U-shaped rod 19 from the plate 16 by lateral motion of the plate 21. When this has been done the creeper is entirely detached from the ski by slipping the loop 2 off of the

toe of the ski. Not only is the creeper proper thus detached but also the plate 21 of the buckle with its associated elements, including the U-shaped rod 19; the creeper may then be replaced on the ski without loosening the pressure member 25 or detaching the creeper from the plate 21. In other words, the adjustment of the strip 15 in the buckle, when once made, need not be disturbed either to remove or replace the creeper from or on the ski. 10 5

It will readily be understood by those skilled in the art that many modifications of our improved ski creeper can be made without departing from the spirit of our invention. We, therefore, desire to secure protection for all such modifications as may come within the scope of the appended claims. 15

We claim:

1. A ski creeper comprising in combination a strip of fur adapted to lie against the lower side 20 of the ski, one end thereof being tapered; a flexible strip attached to such tapered end of the fur strip; a flexible loop carried by the flexible strip; a narrow strip affixed along the longitudinal center of the upper side of said fur strip and extending beyond the other end of said fur strip; an element affixed to the upper side of the ski adjacent the rear end thereof; a U-shaped member detachably associated with said element; and a second element carrying a pressure member 25 adapted to engage a free portion of said narrow strip, said U-shaped member being permanently associated with said second element. 30

2. Means for attaching a creeper to a ski comprising in combination a narrow strip of canvas or similar material affixed to one end of the creeper; a plate affixed to the ski, one end of said plate being bent back upon itself to form a channel; a U-shaped member, one leg of which passes through said channel and is removable therefrom; a second plate, one end of which is bent back upon itself to form a channel, the other leg of said U-shaped member being permanently but rotatably held in said last-mentioned channel; and means for clamping said narrow strip to said 40 second plate. 45

3. A device according to claim 2 wherein said second plate carries upstanding flanges and said clamping means is composed of a pressure member located adjacent said second plate and between said flanges. 50

4. A device according to claim 2 wherein said U-shaped member is provided with means preventing the removal of said member from said first-mentioned channel when said narrow strip 55 is under tension.

5. Means for attaching a creeper to a ski comprising in combination a strip of canvas or similar material affixed to the creeper; a plate affixed to the ski, one end of said plate being bent back 60 upon itself to form a channel; a second plate, one end of which is bent back upon itself to form a channel; a U-shaped member, one leg of which passes through one of said channels and the other leg of which passes through the other of said 65 channels, one leg of the U-shaped member being removable from its channel and the other leg thereof being permanently but rotatably held in its channel; and means for clamping said strip to said second plate. 70
